UNITED STATES PATENT OFFICE.

THOMAS PERKINS SOMES, OF REVERE, MASSACHUSETTS.

RATCHET-DRILL.

SPECIFICATION forming part of Letters Patent No. 309,989, dated December 30, 1881.

Application filed October 25, 1884. (No model.)

To all whom it may concern:

Be it known that I, THOMAS PERKINS SOMES, a citizen of the United States, residing at Revere, in the county of Suffolk and State of Massachusetts, have invented certain new and useful Improvements in Ratchet-Drills; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to "ratchet-drills," so called, in which a continuous rotary movement is effected by an operating-lever with pawls and ratchets acting upon a train of gears, in lieu of an intermittent rotary movement, as hitherto accomplished. My present device relates more particularly to the adaptation and general arrangement of the working parts; and it consists, first, in the construction of compound gears formed with spur and ratchet teeth, and in their disposition upon a secondary shaft in alignment with the shaft of the drill; secondly, in the construction of reversible double pawls similarly mounted upon a common shaft, but oppositely operated by suitable means, whereby the motion of the operating-lever back and forth effects continuous rotary movement of the drill in either direction right or left, as may be desired; and, thirdly, in the general position of the parts relatively one to the other, whereby a very compact, strong, and effective machine is secured.

The drawings accompanying this specification represent in Figure 1 a side elevation, and Fig. 2 a vertical central section, of a ratchet-drill embodying my invention. Fig. 3 is a side elevation of the double pawls, showing their relative positions, while Fig. 4 is a section on line $\alpha\alpha$ of Fig. 1, showing the operative parts by which the pawls are reversed.

In the drawings I have shown the frame at A, formed with an offset, B, centrally bored, and provided with a short fixed shaft or stud, upon which is loosely mounted a miter-gear, C. I have further provided a circular rod or shaft, a, centrally aligned with the drill-shaft

and spanning the sides of the offset, while loosely mounted upon said shaft are two compound miter and ratchet gears, D E, meshing with the gear C. This shaft a does not rotate, but is fixed, being secured at one end in the frame A by a pin or bolt, while its lower end is formed with a head, upon which rests the compound gear E, by which the latter is maintained in its proper position to engage the miter-gear C. These gears I have constructed purposely with the idea of making the machine as compact as possible consistent with strength and with the fewest number of parts, and accordingly have formed their faces with teeth, as is usual in miter-gears, while their peripheries are further provided with ratchet-teeth b b , &c., of such shape that the latter will co-operate with their pawls in either direction in which the gears may rotate. The lower gear, E, is formed with a long hub, c, which extends through and rotates within the bore e in the lower portion of the frame A, while to the lower projecting extremity of said hub is secured a tubular head, F, in which the drill fits and is securely fastened when actively employed. This head may be dispensed with, and the drill-shaft secured directly in a socket formed in the end of said hub. This head F, as shown in the drawings, may be removed and a socket-wrench employed in lieu thereof, whereby the machine is easily adapted in turning nuts where a wrench could not be used. The upper part of the frame is provided with the ordinary screw-feed mechanism, and thus proper pressure is secured upon the object to be perforated. To prevent the frame from turning and maintain it fixed when the operating-lever is actively employed, I have provided a projecting arm or lever, P, which may be made either separable or integral with the frame A.

To operate the train of gears C D E to effect continuous rotary movement in either direction, (right or left,) I have constructed a bifurcated plate, G, with arms f g , through which the shaft a , before mentioned, passes, and thus permits of free movement back and forth of the operating-lever H, attached to the said plate G.

Between the arms f g , and mounted loosely upon a fixed rod, h , are reversible double-

nosed pawls I J, which are alike and similarly arranged, but so disposed that the contiguous noses shall never be actively employed at the same time; and I have so constructed said 5 pawls that by means of a push-pin, *i*, it shall effect an opposite motion of the pawls I J to change the position of their noses with respect to the ratchet-teeth. Thus means are secured by which the drill is made to revolve continuously in either direction to the right 10 or left by the reciprocating movements of the operating-lever *H*.

To effect the requisite change in the action of the pawls by which two of such pawls may 15 be similarly operated and brought in contact with the ratchet-teeth *b b*, &c., I have cut notches *j j'* upon the rear or convex portion of the pawls, while a rock-lever, *K*, is centrally pivoted upon a spring-actuated rod, *k*, 20 while the ends *l l'* of the rock-lever engage in the slots *j j'*, respectively. It is to be understood that the tension of the spring is in the direction of the pawls, and thus exerts its thrust upon the rock-lever *K* to continuously 25 maintain its ends *l l'* in engagement with the notches *j j'* in the pawls. To actuate the lever *K* and rock it upon its pivot to change the action of the pawls, I have inserted a push-pin, *i*, at right angles to said lever, and cut in it a 30 notch or slot, *m*, into which one of the arms of the lever *K* fits. Hence it will be readily understood that a movement of this pin *i* in either direction rocks the lever *K* and operates 35 the pawls in opposite ways to depress and actively employ two of the noses, (at present inactive,) one on each pawl, and move them in opposite directions, while at the same time the other two noses, now being actively employed, are lifted up and disengaged from contact with the ratchet-teeth *b b*, &c.

The operation of this machine is as follows, it being understood that the noses of the pawls, when actively employed, are always operating oppositely—that is, if one is 5 right-hand, the other is a left-hand pawl. Hence in the movement back and forth of the operative lever I will suppose the front nose of the pawl *J* is active and right-handed—that is, it will turn the gear *E* toward the left 10 in the drawings, and thus rotate it from left to right—when the lever *H* is drawn toward the operator, (see Fig. 1,) while the rear nose employed on pawl *I* is acting oppositely, or is left-handed, and is employed when the operator thrusts the lever *H* away from him upon the return or back stroke. Thus the two pawls are alternately active and inactive. The pawl *I* engages the ratchet-teeth *b b* on the compound gear *D*, rotating it to the right in 15 the drawings, and it revolves from right to left, while as it meshes with the miter-gear *C* this is rotated toward the operator, and its rotation is in unison with the rotary movements of the gear *E*, as above described. Thus continuous rotary movement of the gear *E* is effected, and the latter, by means of its hub *c*, to which is attached the tubular head *F*, with

its drill, maintains continual rotation of the latter so long as the lever is reciprocated.

The operation as above described effects 70 rotation of the drill from left to right, and I will suppose it is desired to change this direction and reverse the motion. The push pin or lever is now actuated so as to bring one side of the notch or slot *m* in it against 75 the arm of the rock-lever *K* engaged therein, and the latter is actively employed, (see Fig. 4,) and its extremities *l l'* are moved away from the sides of the slots *j j'*, with which they are in contact, until they engage the opposite 80 sides of said slots, when the pressure from the lever *i* depresses the oppositely-disposed free or inactive noses of the pawls until they engage the ratchet-teeth and they become active. The same motion of the pawls has now 85 raised and disengaged the two other noses of the pawls which have just been actively employed, and has rendered them inoperative by lifting them away from the ratchet-teeth *b b*, &c. Movement of the lever *H* now effects 90 rotation of the drill-head and drill in the reverse direction, or from right to left.

By means of the above device I am enabled to employ the lever in a path of movement at right angles to the drill, and thereby overcome 95 some of the disadvantages resulting from such movements when parallel with the drill-shaft.

I have thus described, briefly, the various operative parts of the ratchet-drill embodying my invention; but I do not desire to be limited to the precise construction of the parts herein shown, as various simple modifications may be substituted therefor; but I consider the spirit of the invention consists in the co-operation with the compound miter and ratchet gears of the reversible oppositely-arranged double pawls, whereby the same reciprocations of the operating-lever shall rotate the drill either to the right or left, as is desired.

I claim the following:

1. In a ratchet-drill, the combination, with the frame carrying the drill-shaft, of the compound miter and ratchet gears and the oppositely-arranged double pawls, whereby change in position of the latter effects change in the rotation of the drill, substantially as described.

2. In a ratchet-drill, the combination, with the frame and its miter-gear, of a shaft centrally aligned with the drill-shaft, and carrying compound miter and ratchet gears and the oppositely-operating double pawls, whereby continuous rotary movement, either right 120 or left, is obtained, substantially as stated.

3. In a ratchet-drill, the combination, with the frame, of a train of gears loosely mounted and adapted to co-operate with two oppositely-operating double pawls and their operative mechanism, by which to reverse the position of said pawls, and thus obtain continuous rotary movement, either right or left, substantially as herein described.

4. In a ratchet-drill, the frame A, gear C, meshing with the compound miter and ratchet gears D E, loosely mounted on the shaft a, and hub c, in combination with the double slotted pawls I J, spring-actuated rock-lever K, and push-pin i, operating substantially in the manner herein specified.
5. In a ratchet-drill, the combination, with the ratchets and double pawls, of the spring-actuated rock-lever and push-pin, by means of which the opposite ends of said pawls are rendered active or inactive and the rotation of the drill changed to either right or left, as may be desired, substantially as stated.
- In testimony whereof I affix my signature : 5
in presence of two witnesses.
